MARKING DEVICE

Application filed June 2, 1927. Serial No. 196,138.

This invention relates to improvements in marking devices. More particularly it relates to devices by which the authenticity, origin or identity of a particular specimen of a manufactured product may be determined by examination of the specimen, when it is offered for sale in commerce or has been used for its appointed purpose; and although the marking accomplished by practice of the invention may be employed for conveying any sort of intelligence, it is believed that its greatest utility will be found where the information conveyed has some particular reference to the article which bears the mark. This is especially useful in cases where a permanent associating of the desired information with the product is not readily effected by a printed label or inscription. The invention is herein illustrated as applied for identification of a rope.

For identifying a rope as being of particular make, or as being owned by a particular navy or company, it has heretofore been proposed to lay a yarn of some certain dyed color among the other yarns of the rope. But colored yarns have been used by so many different persons, and for so many purposes, and are so readily open to challenge and to counterfeiting, that this identification means has ceased to be satisfactorily distinctive. It is one feature of the present invention that it provides a distinctive yarn in the rope, which yarn is a regular stress-bearing part of the rope like the other yarns. It is another feature that this may be, not merely, an identification means, but that it may have the peculiar quality of being a secret or private mark, not observed by an ordinary person, but capable of being made to flash out in clear and unmistakable brilliancy when an informed person applies the proper test.

For such purposes it is requisite that the treatment to which the test yarn is subjected should not harm the strength or other qualities of the component fibres, and that the identification characteristics should persist in the yarn notwithstanding that the rope undergoes any sort of experience, such as becoming soaked with oil; or with fresh or salt water;

or becoming filled with coal dust, dirt or grit of any kind.

The invention provides for the preliminary treating of the marking element, which may be one of the regular yarns of the rope (or a structural part of the article which is to be marked, whatever that article may be), with a substance which does not change the aspect of the yarn (or, at preference, with a substance which does clearly change its aspect), but which responds in a distinctive and unmistakable way when the preliminarily treated yarn is subjected to a certain special test treatment. The test treatment may consist of subjecting the yarn to a certain change of condition and it is particularly impressive and convincing if applied to all of the associated yarns together, treated and untreated. The particular test treatment here chosen for illustrating the invention is to expose the yarns together to ultra violet rays; and the preliminary treatment is to immerse the test yarn in a coating, impregnating or reacting substance such that the yarn to which it has been applied becomes fluorescent to a distinctive degree in ultra violet rays.

It has been discovered that such a preliminary treatment can provide a permanent fixation, without damaging the fibre, which fixation is not itself capable of being dissolved, or damaged by, or of reacting with, anything into contact with which the rope comes during the rope's life time of normal usage, but remains always capable of responding to the test treatment.

In a preferred embodiment of the invention a yarn of hemp fibre, or of sisal, or of other material like that of which the identifiable rope is to be made is to be treated with a dye which produces in the yarn a color which as ordinarily seen is approximately the same as that of the rope, but which possesses a distinctive ultra violet fluorescence. An example is found in the sodium salt of the sulfonic acid of methylated primuline base, which produces a color in the yarn that is practically indistinguishable from that of untreated yarn, when seen in daylight or under ordinary electric light, but which has a striking whitish yellow fluorescence when

85

90

95

100

seen under ultra violet light. When a yarn treated with this is incorporated in a rope with untreated yarns, this yarn is not distinguishable from the others by ordinary light; but under the changed conditions of observation produced by ultra violet rays it is distinguished not only by its whitish yellow fluorescence, but by the fact that the other yarns appear slightly fluorescent with a blue color, due to the oil with which the fibre has been treated in the working of the material into yarn as is customary in the manufacture of rope. These visual characteristics of the rope, with the test yarn standing out beautifully and clearly from the others, have proven to be practically unaffected by many hours endurance test of exposure to fresh water, sea water, gasoline, lubricating oil and steam. This dye is listed in the standard reference book of dyestuffs used by the color trade, entitled "Colour Index of the Society of Dyers and Colourists", published in January 1924 by the society at Bradford, England, which gives the formulæ and methods of preparation with trade names and scientific names of commercial dyes, so that the above mentioned dye can be more simply indicated and identified by reference to this book and by its number therein, thus: E. C. I., No. 816.

In another application of the invention a yellow dye may be employed which leaves the yarn yellow in ordinary light but makes it so that it does not fluoresce at all under the ultra violet rays, merely appearing a deep purplish brown in color. This likewise is distinctive because the ordinary yarns fluoresce to a blue color as above indicated. Tests have shown that this blue fluorescence persists throughout the life of the rope. Such a non-fluorescing dye, giving a pale yellow aspect to the yarn but little different from the aspect of untreated yarn, and remaining unchanged for practical purposes by the above endurance test, is the sodium salt of 2:2' disulfostilbene 4:4' disazo-bis-phenetole, E. C. I., No. 365.

In another application of the invention a dye is used which has the characteristic that the yarn to which it has been applied is indistinguishable from yarn to which it is not applied, but which in ultra violet rays, fails to fluoresce, being barely seen as a purplish brown, while the ordinary yarn fluoresces to a blue. This is the sodium salt of diphenylurea p, p'-disazo-bis-salicylic acid, E. C. I., No. 346; and this remains distinguishable notwithstanding application of the endurance test above stated.

For still another application of the invention, it may be preferred to have a yarn which is readily distinguishable from the others by ordinary light, being in this respect comparable to yarns which have been used for identification purposes hitherto in rope, and which

confirms or verifies itself as being genuine by responding under ultra violet rays by fluorescing distinguishably from the other yarn. An example of such is a mixture of the sodium salts of the monosulfonic acids 70 of more highly thionated dehydrothio-p-toluidine derivatives together with some dehydrothio-p-toluidine monosulfonic acid, E. C. I., No. 812. This dyes the yarn a very pale yellow that is easily distinguishable 75 from the other fibre, and which fluoresces to a whitish yellow. Another example of this class is the hydrochloride of tetramethyldiaminodiphenylketone imine, E. C. I., No. 655, which is of bright yellow color by ordinary light and which fluoresces to a bright yellow color distinctive from the other fibres; and another is the hydrochloride of diethyl 80 m-aminophenolphthalein, E. C. I., No. 749, which fluoresces pink. Experiment shows 85 the former of these less stable under persistent exposure to water.

One way of applying this or other of the colors is to twist a yarn which has been treated with it with a yarn which has been 90 dyed to a like color with non-fluorescent material. These when incorporated together into rope look alike, in ordinary light, but under the changed conditions which prevail in ultra violet rays the twisted unit appears 95 in a series of sections alternately fluorescing and not fluorescing. The principle may be applied whether the twisted yarns look alike in ordinary light or are distinguishable.

By means of differing selections and combinations a wide variety of marking is thus obtainable. If it be desired, the products of a company using the invention may be arranged so that the identifying characteristics do not appear to the ordinary observer, 100 yet respond strikingly when tested by examination under ultra violet rays. Such a keeping private of characteristics which identify the goods renders counterfeiting 105 more difficult.

Although the particular form of the invention herein described relates to the use of the fluorescent material as a dye, it is possible also to use it by mixing a suitable inert material with the grease which is applied to the 110 fibre during its working in process of manufacture of the yarn, which would produce, in a particular yarn which had been thus treated, a degree of fluorescence differing from that of ordinary yarn comprising other 115 parts of the same rope. Or, other fluorescent material may be incorporated with the grease in the working of the fibres, while making the yarn.

Other variations may be made. And while 120 the description herein shows an application in which the marking substance takes the form of an element of the article marked, as a yarn of a rope, it will be understood that the substance applied, which is to fluoresce 130

5 distinctively does not necessarily have the form of the element or article to which it is applied. It is intended that the patent shall cover, by suitable expression in the appended claims, whatever features of patentable novelty exist in the invention disclosed.

10 For an illustrative example, the practice of the invention with E. C. I. No. 816 may be considered. The manila, sisal or other 15 yarn which is to constitute the identification means may be run through a vat containing a solution of this dye in water. In this particular instance the dye weighed 1% of the weight of fibre to be dyed, and was dissolved 20 in 25 volumes of water; and it was found that after sixty seconds immersion, and drying, the yarn is indistinguishable in ordinary light from other yarn of the same kind which has not been thus dyed; but that when 25 made into a rope with this other yarn, and seen in ultra violet rays, the dyed yarn stands out with a whitish yellow fluorescence, from the mass of other yarn which fluoresces blue. Experimental tests indicate that the fluorescence characteristic will persist 30 throughout the life of the rope in its normal usage, subject to its normal vicissitudes of exposure to abrasion, to solution and to chemical reaction.

35 For the following illustration of the invention reference is made to the accompanying drawings, wherein:

Figure 1 represents a bit of rope in which one of the yarns has been prepared to respond 40 to the test treatment and is distinguishable from the others even before the test; and

Figure 2 represents in diagrammatic form the application of a test treatment using ultra 45 violet rays whereby the prepared yarn fluoresces to a brilliant yellow while all of the other yarns subjected to the same rays at the same time fluoresce to a dull blue.

In the drawings, Figure 1, which represents the rope as seen in natural light, the 50 prepared yarn is marked 10 and is stippled lightly so that its course through the strand in the rope can be traced. This stippling may indicate the presence of the dye, which, in practice may at choice be so much like the 55 color of the other yarn as to be not readily or certainly distinguishable from them under ordinary inspection, or may be readily distinguishable from them. Or, if desired, this yarn may be readily distinguishable from others in ordinary light because of being of 60 different texture or because of containing some non-fluorescing, visible dye, the presence of which is a matter of choice and not a feature of the invention. However this 65 may be, the diagrammatic showing in Figure 2 indicates the appearance when the test treatment of ultra violet rays is applied. The observer being with the rope which is to be tested in a place of utter darkness, wherein 70 the rope and all parts of it are invisible,

75 indicates apparatus generating ultra violet rays which may be considered to have a wave length, measured in Angström units somewhere in the range between 200 and 4000, this being the range of light waves, otherwise 80 called waves of radiant energy or electromagnetic waves, covering the four octaves next below the single octave covered by the visible spectrum, ranging from 4000 to 7000 Angström units in length. Upon the setting 85 of the apparatus into action, producing the ultra violet rays, without the rope being within their reach, the field continues in darkness as before; but upon the thrusting of the rope containing the prepared yarn 90 into the field of ultra violet rays the yarn 10 becomes plainly visible with a whitish yellow radiant aspect, and the other yarns 12 of the rope become visible as a dim blue. Thus the prepared yarn stands out in visual 95 aspect in sharp contrast to the others and constitutes a mark on the rope which becomes readily distinguishable upon the mere application of the specified rays, the explanation being that the impinging of the said rays 100 upon the fluorescent substance in the yarn produces a reaction such that the said rays become broken up or converted in part to rays whose waves are of a length which is visible to the human eye. The other yarns 105 fluoresce to the stated blue, dimly, and in the particular experiment which is being described, because of the presence in them of a small quantity of oil which produces this 110 result; but in the absence of this oil or other ingredient of like effect these other yarns would remain absolutely invisible, as do other articles which are within the range of the applied rays, as the table top or the operator's hand, but are not thus prepared with 115 a fluorescing substance.

When it is desired to test any rope for discovery whether it contains a special identification characteristic, a few inches of the 120 end of the rope may be unlaid so as to display the various yarns; and then in a darkened chamber these may be exposed to ultra violet rays produced by any suitable method, of which a number are known. For this purpose mercury arc lamps radiating through 125 quartz are readily available in the market and are satisfactory. Also, a carbon arc is useful, in conjunction with a filter of special glass which removes the visible portion of the spectrum. If the rope has been used it 130 may be advisable to wash thoroughly the yarns which have been unlaid from its end, in order to remove all foreign matter; and for this purpose a washing in gasoline is effective in addition to a washing in water. But whether this be done or not, the test is applied by simply thrusting the rope or the unlaid end of it into the field of ultra violet rays, and then observing the aspect 135 which it there assumes.

It will be perceived that the invention thus described is a specific application of the generic improvement which consists in providing, in the case of rope, a yarn which reacts differently from the way in which the other yarns react when all together are subjected to a test treatment. The treatment producing the reaction may be exposure to a particular kind of light, as the ultra violet rays; or polarized light; or light which has passed through a color filter, which may be mentioned as other examples. The distinctive and novel characteristic of the invention is that the mark which constitutes the test appears as a result of a reaction from the application to the article of conditions which are changed from those under which the article ordinarily exists or is viewed.

I claim as my invention:

1. An improvement in the art of marking, comprising the combining, with the article which is to be marked, of a substance which fluoresces with a distinctive aspect under light rays which are outside of the range of rays normally visible to the human eye, thereby constituting a mark on said article which becomes distinctive when said outside rays are applied.

2. An improvement in the art of marking whereby the marked article has had treatment at predetermined loci, thus permitting contrast between said predetermined loci and the adjacent portions of the article, with a substance, constituting the mark, which under ordinary light resembles said adjacent portions of the article, but which under the influence of radiant energy of a wave length less than that of ordinary light fluoresces with a distinctive aspect.

3. An improvement in the art of marking articles composed of a plurality of structural elements, comprising treating one of said structural elements with a substance which fluoresces with a distinctive aspect under the influence of radiant energy of a wave length less than that of ordinary light, whereby the mark appears in the structural shape of the treated element when the article as a whole is subjected to the action of such energy.

4. An improvement in the art of marking articles composed of yarn, comprising the introduction into the article, among the yarns, of a yarn which is diverse from other yarns therein as regards its fluorescent properties.

5. An improvement in the art of marking articles made of yarn, comprising the immersing of the material composing a yarn, preliminary to the assembling of all the yarns to make the article, in a substance whose effect is to make the yarn to which it is applied visibly respond diversely from the way in which yarns not thus treated respond when subjected to rays of light which are outside of the range of rays normally visible to the human eye.

6. An improvement in the art of marking comprising the combining with the article which is to be marked of a dye which fluoresces distinctively under ultra violet rays; said dye being arranged on the article in a pattern which is obvious on the article when viewed directly under ultra violet rays. 70

7. An improvement in the art of marking rope, comprising the treatment of a yarn of the rope with a substance which produces in it a fluorescence under ultra violet rays diverse from the fluorescence under the same rays of other yarns not so treated. 75

8. An improvement in the art of marking rope, comprising the incorporating in the rope of a yarn which under ordinary light resembles the other yarns, but is specially treated with a substance such that under ultra violet rays it appears diverse from the other yarns which are not similarly treated. 80

9. An improvement in the art of marking rope, comprising the incorporating in the rope of a yarn which is responsive to light diversely from the responsiveness of other yarns of the rope, when the light by which it is viewed is altered from the normal light in which objects are seen. 90

10. An improvement in the art of marking comprising the application to the article to be marked of an extraneous substance capable, when subjected to the action of energy of given characteristics, of emitting energy of different characteristics. 95

11. An improvement in the art of marking comprising the application to the article to be marked of an extraneous substance capable, when subjected to the action of energy of given characteristics, of emitting waves of visible radiant energy. 100

12. An improvement in the art of marking comprising the application to the article to be marked of an extraneous substance which when stimulated by waves of ultra-violet radiant energy will emit waves of radiant energy falling within the visible range. 105

13. A new article of manufacture comprising an industrial product with which is associated, as a means of identification, a normally dormant extraneous substance capable of fluorescing with a distinctive aspect. 110

14. A new article of manufacture comprising an industrial product with which is associated, as a means of identification, an extraneous substance which fluoresces with a distinctive aspect under the influence of radiant energy having a wave length less than that of ordinary light. 115

15. A new article of manufacture comprising an industrial product with which is associated, as a means of identification, an extraneous substance with fluoresces with a distinctive aspect when subjected to the action of ultra-violet rays. 120

16. A new article of manufacture comprising a rope one of the yarns of which, as a 125

means of identification, is impregnated with a dye which is of substantially the same color as the rope itself, but which, under ultra-violet rays, fluoresces with a distinctive

5 aspect.

Signed at Boston, Massachusetts, this twenty-third day of May, 1927.
